TRANSFER DEVICE FOR ADHERING SHOULDER LABELS TO BOTTLES

Sidney T. Carter, Shrewsbury, Mass., assignor to Geo. J. Meyer Manufacturing Co., Cudahy, Wis., a corporation of Wisconsin

Filed Aug. 27, 1959, Ser. No. 836,496

7 Claims. (Cl. 216—54)

This invention pertains to labeling machines more especially to an improved transfer device designed primarily to take a shoulder label from a picker at a transfer station and to apply the label with firm pressure to the shoulder portion of a bottle, although, as herein illustrated and described by way of example, the transfer device is capable of taking from the picker a plurality of labels, only one of which is a shoulder label, and affix them firmly to a bottle.

In the embodiment herein disclosed the transfer device is of the pneumatic or suction type, such as has come to be known in the art as a "grip finger assembly" and comprises supporting means for label-contacting pads operative, by suction, to grip the uncoated sides of adhesively coated labels adherent to the picker and remove them from the latter and transfer them to the article to be labeled. The grip finger assembly of the present invention is primarily designed for use in a labeling machine of the kind wherein the articles to be labeled are moved by a conveyor, one after another in succession along a predetermined path, and while so moving, receive labels from a grip finger assembly located at one side of said path, the grip finger assembly, at times, moving along said path concomitantly with the article to which the labels are being applied and at the same linear velocity as the article.

A machine of the type just referred to is more fully disclosed in the copending application for Letters Patent Serial No. 551,012, filed by Sidney T. Carter on December 5, 1955, now Patent No. 2,940,630 issued June 14, 1960.

In order to insure the firm adhesion of the label to the bottle, it has been found desirable to hold the label in adhering contact with the bottle for an appreciable period of time, this being particularly true with reference to the shoulder label, since the shoulder portion of the bottle is curved both horizontally and vertically.

An object of the invention is to provide improved and simple apparatus for applying a label to the shoulder of a bottle while the latter is moving uninterruptedly along a predetermined path and which is designed to insure firm contact of the label with the bottle.

A further object is to provide an improved grip finger assembly of the suction type, and simple and effective means associated therewith for applying force to the label-carrying suction pad whereby the label is held in firm contact with the bottle while the latter is moving along a predetermined path.

A further object is to provide an improved grip finger assembly of the suction type and devices associated therewith whereby, while the label-carrying suction pad is in label-contacting position relatively to the shoulder of the bottle and is moving with the bottle along a predetermined path and at the same linear velocity as the bottle, positive force is applied to the pad such as to conform the pad to the sloping surface of the bottle shoulder.

A further object is to provide an improved grip finger assembly of the above-named type which moves along a

2

predetermined path concomitantly with a bottle while affixing a label to the bottle, and having devices operative to apply force to the suction pad as it moves along with the bottle to press the label into contact with the shoulder of the bottle, and having additional means for applying positive force to the pad, after the pad has traveled a predetermined distance along said path with the bottle, thereby to increase the pressure of the pad against the label.

A further object is to provide an improved grip finger assembly of the suction type and devices cooperable therewith whereby the label-contacting surface of a suction pad may be disposed in accurately parallel relation to a picker while at a transfer station, and at the same inclination to the vertical as the label-receiving surface of a bottle shoulder when the pad is in label-applying position, and whereby the pad is held accurately in the latter position while the pad moves with the bottle for a predetermined distance.

In the attainment of the above objects, the invention provides, in a labeling machine of the kind above referred to, a fixed horizontal elongate member parallel to the path along which a bottle to be labeled travels, and which is operative, by engagement with a part of the carrier for the label pad, to apply force for holding the label-contacting face of said pad at the same angle of inclination to the vertical as the label-receiving surface of the bottle shoulder while the pad moves concomitantly with the bottle for a predetermined distance along said path.

The invention further provides a part which engages said pad carrier, after the latter has traveled with the bottle through a fractional portion of said predetermined distance, to apply additional and positive force to the pad carrier for increasing the pressure of the pad against the label.

Other and further objects and advantages of the invention will be pointed out in the following more detailed description and by reference to the accompanying drawings, wherein:

Fig. 1 is a fragmentary elevation partly in vertical transverse section showing a grip finger assembly according to the present invention arranged at one side of the article conveyor, the grip finger assembly being shown in full lines in the label-affixing position and in broken lines at the transfer station at which it receives labels from the picker;

Fig. 2 is a fragmentary side elevation looking from the right-hand side of Fig. 1 showing the upper portion of the grip finger assembly with details of the support for the shoulder pad;

Fig. 3 is a fragmentary elevation, to larger scale than Fig. 1 and partly in vertical section, showing, in further detail, the means for adjustably supporting the normally stationary bar which positions the shoulder label pad carrier as the latter moves along the conveyor path with the bottle to be labeled;

Fig. 4 is an elevation of the picker, illustrated in broken lines in Fig. 1, showing in dotted lines the position of the body and shoulder label pad carriers relatively to the picker blades and labels as the pad carriers stand at the transfer position;

Fig. 5 is a fragmentary diagrammatic view, but omitting many of the parts shown in Fig. 1, showing the grip-finger assembly as having nearly approached the label-applying position and at the instant at which the carrier for the shoulder label pad is beginning to swing downwardly toward label-applying position;

Fig. 6 is a diagrammatic side elevation, to larger scale than Fig. 1, showing the carrier for the shoulder label pad separate from other parts; and

Fig. 7 is a fragmentary diagrammatic end elevation,

partly in vertical section, illustrating a labeling machine of a type in which the grip finger assembly of the present invention may be useful.

Referring to Fig. 7, the character Q indicates the base portion of the frame of a machine of the kind more fully disclosed in the copending application for Letters Patent Serial No. 551,012, filed December 5, 1955, by Sidney T. Carter, said frame supporting various parts, including bearings for the main shaft S upon which are mounted cams (not shown) for actuating those elements of the machine which go through a predetermined cycle once for each rotation of the shaft S in functioning to apply a label. Only one side of the machine is shown in Fig. 7, although it is to be understood that if the machine is to apply labels simultaneously to opposite sides of an article, the machine will be provided with label-applying devices at both sides of the conveyor path. As shown in Fig. 7, a conveyor C, which may be of conventional type, is so driven as to move the article to be labeled, for example, the bottle A, uninterruptedly along a predetermined path through the several zones in which successive labeling operations take place.

As shown in Fig. 7, the machine comprises a gum box G containing a gum-elevating roll E which supplies gum to a corresponding transfer roll E' which is carried by a rocking lever L so as to transfer gum from the roll E' to the surface of the picker P. This picker is desirably of the type more fully disclosed in the patent to Carter 2,414,019, January 7, 1947. The picker P receives a coating of gum from the transfer roll E' while the blades of the picker are closed, and the picker is then swung so as to contact its gummed surface with the endmost labels in the magazine (not here shown), this magazine having compartments for body and shoulder labels, respectively. The picker blades then open, while contacting the endmost label in the magazine compartments, thereby spreading the gummy adhesive, and it then swings back to the transfer position shown in broken lines in Fig. 1 and in full lines in Fig. 7, its relatively movable blades remaining separated, as illustrated in Fig. 4. With the picker blades in this separated condition and with the end portions only of the labels L and L', respectively, adhering to the respective blades at the transfer station, the label-contacting faces of the blades are disposed in a plane which inclines downwardly and toward the vertical plane defined by the axis of the bottle as the latter approaches the position where it is to receive the labels.

As shown in Fig. 7, the transfer station, represented by the full-line position of the picker P, is spaced a substantial distance from the bottle which is to receive the labels. While the picker P dwells in the position shown in Fig. 7, the grip finger assembly F is moved in a counterclockwise direction so as to contact its label-transfer pads P' and P² with the labels L and L', respectively, the grip finger assembly then continuing its upward motion to the left as viewed in Fig. 7, carrying the gummed labels with it and eventually pressing the labels into contact with those portions of the bottle surface which are to receive them, while the picker returns for the reception of a fresh coating of gum.

It may be noted that the machine in which the grip finger assembly of the present invention is to be employed is one in which the bottles to be labeled move, one after another in succession, along a predetermined path and receive the labels while they are so moving.

While a single grip finger assembly is here illustrated, it may be understood that if the machine be designed to apply labels to a plurality of articles simultaneously, then in that event the machine will comprise a plurality of label magazines corresponding in number to the number of articles to be labeled simultaneously, and there will be grip finger assemblies and pickers for transferring labels from each of the respective magazines.

As here illustrated, the grip finger assembly F is secured at its lower end to a rock-arm M (Fig. 1), which is fixed

to a shaft K (Figs. 1 and 7), this shaft being arranged to rock and also to move endwise in suitable bearings, one of which is indicated at B (Fig. 7). Any suitable means, receiving its motion from the main shaft S, may be employed for imparting these motions to the rock shaft, for example, such means as is more fully disclosed in the copending application Serial No. 551,012 above referred to.

As here illustrated, the grip finger assembly F is provided with two label-applying pads P' and P², respectively, the pad P' being designed to apply the shoulder label to the bottle, and the pad P² being designed to apply the body label. Since the present invention is primarily concerned with the means for applying the shoulder label, a detailed description of the means for applying the body label is omitted, it being understood that for applying the body label, a label-applying pad and carrier therefor, generally similar to that shown in the copending application of Sidney T. Carter, Serial No. 815,878, filed May 26, 1959, may be employed. Whatever the specific means for applying the body label, it may be understood that the pads P' and P² will be provided with suction orifices or ports of customary type, and that suitable means (not here shown), for example, an air pump and automatically actuated valves, will establish suction at these ports at the proper time in the cycle to enable the pads to grip the labels and remove them from the pickers, the suction at these ports being broken at the proper time in the cycle to permit the pads to leave the labels in adhering contact with the bottle while the grip finger assembly returns to the transfer station.

The grip finger assembly desirably includes a casting which is secured to the rock-arm M in any desired manner, and which supports brackets in which is mounted a shaft 27 (Fig. 1), forming a pivotal axis for a lever 29, this lever being of rigid construction and having the carrier Z' for the body label pad P² secured thereto. To the outer side of this lever 29, near its upper end, there is attached a bracket member 32, preferably by bolt-and-slot connections so that the bracket may be moved up and down for adjustment; and to the upper end of this bracket, bearing member 36a (Fig. 5) are attached in which are mounted the ends of a shaft 37 on which is pivotally mounted the carrier Z² for the shoulder label pad P'. It will be understood that the rock-arm M and the lever 29 and associated parts constitute a movable support for the pad-carrier Z² such that the latter moves bodily along and parallel with said path, at times, and also rocks toward and from said path.

This carrier Z², as more fully shown in Fig. 6, has a flat surface to which the pad P' is secured. The pad P', as is customary in apparatus of this type, is of resiliently yieldable material, such as rubber, and is attached to the carrier in any conventional way. The carrier Z² has a shoulder 100 (Fig. 6) having a lower surface 101, which, at times, contacts the bottom of a slot N (Fig. 2) in the upper end of the bracket 32. A coil spring S' embraces the shaft 37 and exerts pressure against the pad carrier Z² tending to turn the latter in a clockwise direction so as to keep the surface 101 in contact with the bottom of the slot N.

The pad carrier Z² is provided with a recess 102 (Fig. 6) in its lower part which receives a freely rotatable roller 103, and the carrier Z² also has a cam face 104 for a purpose hereinafter described.

In Fig. 1, a hold-down device H is shown as engaging the top of the bottle in order to prevent the bottle from changing its position after having been oriented preparatory to the application of the label, this hold-down being, for example, of the kind more fully disclosed in the above copending application Serial No. 551,012. This hold-down is supported by fixed angle bars H² and H³, the latter having a horizontal flange H⁴ which, as more fully illustrated in Fig. 3, is provided with a vertical screw-threaded bore which receives an externally screw-

threaded sleeve 105 which may be turned for adjusting it upwardly or downwardly, and which is held in adjusted position by nuts 106 and 107. Within this sleeve is arranged the vertical portion 108 of a rigid member, which, at a point below the lower end of the sleeve, is bent, as indicated at 109, to provide a horizontal portion 110 which extends toward the conveyor path and which supports, either as an integral extension of the part 110 or as a separate part, an elongate abutment member 111, here shown (Fig. 3) as circular in transverse section and which extends horizontally a substantial distance along the conveyor path. The length of this abutment member or bar is at least as great as the length of the path of travel of the grip finger assembly along the conveyor path while holding the label in contact with the bottle. As shown in Fig. 3, pins 112 and 113, extending through openings in the member 108, engage washers 114 and 115 at the upper and lower ends of the sleeve 105 and thus prevent axial motion of the member 108 relatively to the sleeve. In order to prevent the part 108 from rotating about its own axis, the upper end of the member 108 is provided with a transverse opening which receives a pin 116, the left-hand end of which, as viewed in Fig. 3, extends through a slot in the member H³. By this means it is possible to adjust the abutment bar 111 upwardly or downwardly and to retain it in adjusted position while the axis of this member 111 remains accurately parallel to the conveyor path at all times.

The horizontal flange H⁴ is provided with another opening which receives a bolt, by means of which a bracket member 117 is secured to the part H⁴, this bracket having a substantially horizontally lower portion 118 which is provided with a screw-threaded opening for the reception of a stud on which is mounted a freely rotatable roller 119 (Fig. 1).

In the operation of this device, and assuming in the first place that the picker and grip finger assembly occupy the relative positions indicated in broken lines in Fig. 1, which is the transfer position, it will be noted that the label-contacting faces of the shoulder label pad P' and the body label pad P² are accurately aligned and in the same plane so that both of these pads may make gripping contact with the labels L and L', respectively, supported at this time by the picker.

As indicated in Fig. 4, the blades B^x and B^y of the picker have been separated so that only the ends of the labels are adhering to the picker blades, the inner edges of the blades being so spaced as to permit the pads P' and P² to pass between them. From the transfer position the grip finger assembly now moves upwardly in a counterclockwise direction, taking the labels from the picker, until it reaches a position such, for example, as indicated in Fig. 5, where the body label pad P² has nearly contacted the bottle A. At this time the roll 103, mounted on the carrier Z² for the shoulder label pad P', has come into contact with the abutment member 111 and has lifted the surface 101 of the carrier Z² from the bottom of the notch N in the bracket 32 and has swung the carrier Z² in a counterclockwise direction in opposition to the spring S so that the pad P' is approaching the shoulder surface D of the bottle. Further movement of the grip finger assembly to the left, from the position of Fig. 5, moves the shaft 37 bodily to the left, but since roll 103 is now in contact with abutment rod 111, the carrier Z² will swing until the pad P' brings the shoulder label into contact with the bottle shoulder. The parts remain in this position while the grip finger assembly initiates its motion longitudinally of the conveyor path, and when the assembly has reached approximately the mid-point of its travel in this direction, the cam face 104 of the carrier Z² engages the roll 119, as shown in Fig. 1, the surface 104 being so shaped that by contact with the roll 119 the carrier Z² is urged further to the left by additional and positive force tending to press the label more firmly into contact with the bottle. However, un-

der ordinary circumstances, the actuation of the carrier Z² by the contact of roll 103 with the abutment 111 is sufficient to provide the desired affixing of the label to the shoulder surface.

At the end of the travel of the grip finger assembly longitudinally of the conveyor path, the assembly is swung away from the bottle, and while in its retracted position is moved backwardly along the conveyor path to its initial position in readiness for the repetition of the cycle by means such as more fully described in application Serial No. 551,012 above referred to.

By the arrangement above described, it is possible to apply the shoulder label firmly and securely to the sloping surface of the bottle shoulder, even though the surface may not be as smooth or regular as it should be theoretically. It will be noted that the pressure applied in affixing the label is a positive pressure and not merely a spring pressure, so that the label is pressed into firm contact with the shoulder surface of the bottle.

While one desirable embodiment of the invention has herein been illustrated and described by way of example, it is to be understood that the invention is broadly inclusive of any and all modifications falling within the scope of the appended claims.

I claim:

1. In a machine for applying a shoulder label to a bottle while the bottle is being moved uninterruptedly by the conveyor along a predetermined path, and wherein a suction pad receives a shoulder label from a picker at a transfer position and affixes it to the shoulder of the moving bottle, and wherein a movable support for the pad carries the latter from the transfer position to a label-affixing position, means operative to move the support, after the pad has taken the label from the picker, to an affixing position adjacent to the bottle, and wherein the pad support, when in the last-named position relatively to the bottle, moves bodily concomitantly with the bottle along said path for a predetermined distance, in combination, substantially unyielding means operative positively to hold the pad in label-affixing relation to the shoulder surface of the bottle while the support is moving along said path.

2. In a machine for applying a shoulder label to a bottle while the bottle is being moved uninterruptedly by a conveyor along a predetermined path, and wherein a suction pad receives a shoulder label from a picker at a transfer position and affixes it to the shoulder of the moving bottle, and wherein a movable support for the pad carries the latter from the transfer position to a label-affixing position, means operative to move the support, after the pad has taken the label from the picker, to an affixing position adjacent to the bottle, and wherein the pad support, when in the last-named position relatively to the bottle, moves bodily concomitantly with the bottle along said path for a predetermined distance, in combination, substantially unyielding means operative positively to hold the pad in label-affixing relation to the shoulder surface of the bottle while the support is moving along said path, and means operative to increase the pressure exerted by the pad after the support has traveled along said path for a predetermined distance.

3. In a machine for applying a shoulder label to a bottle while the bottle is being moved uninterruptedly by the conveyor along a predetermined path, and wherein a suction pad receives a shoulder label from a picker at a transfer position and affixes it to the shoulder of the moving bottle, and wherein a movable support for the pad carries the latter from the transfer position to a label-affixing position, means operative to move the support, after the pad has taken the label from the picker, to an affixing position adjacent to the bottle, and wherein the pad support, when in the last-named position relatively to the bottle moves bodily concomitantly with the bottle along said path for a predetermined distance, having means so connecting the pad and the pad support

7
that the label-contacting surface of the pad may be caused to incline at approximately the same angle as the shoulder of the bottle, a fixed member having an elongate surface which extends parallel to said path, and a part which cooperates with said surface of the fixed member, as the pad support nears the label-affixing position, positively to tilt the pad into operative relation to the bottle shoulder.

4. A machine according to claim 3, further characterized in having a pad-carrier pivotally connected to the support to rock about an axis parallel to the conveyor path, and wherein said fixed member is a fixed rail parallel to said path operative, as the support moves along said path, by contact with the pad-carrier, to hold the pad in label-adhering relation to the shoulder of the bottle.

5. A machine according to claim 3, further characterized in that said fixed rail is of a length at least as great as the distance through which the support travels along said path, and a roller on the pad-carrier which, by contact with said rail, moves the pad into label-affixing position relatively to the shoulder surface of the bottle

10 and holds it in such position while the support is moving with the bottle.

6. A machine according to claim 4 wherein said fixed rail is of a length at least as great as the distance through which the support travels along said path, a roller on the pad carrier which, by contact with said rail as the support moves along said path, holds the pad in affixing relation to the bottle shoulder, an actuator located intermediate the ends of the path of travel of said support, and a cam element on the pad carrier which, by contact with said actuator, increases the pressure of the pad against the bottle.

15 7. A machine according to claim 6, further characterized in that the actuator, which contacts the cam element on the pad-carrier is a roller which turns about a fixed vertical axis located at a point intermediate the ends of the travel of the support along said path.
